(57) **CLAIM**

The ornamental design for a pair of in ear headphones, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is a perspective view of a pair of in ear headphones showing our new design;

FIG. 2 is a front view thereof;

FIG. 3 is a rear view thereof;

FIG. 4 is a side elevation view of a pair of in ear headphones with one in ear headphone shown separately for ease of illustration;

FIG. 5 is an opposing opposite side elevational view of a pair of in ear headphones with one in ear headphone shown separately for ease of illustration;

FIG. 6 is a top view thereof; and,

FIG. 7 is a bottom view thereof.

The broken lines showing the environment in the Figures are for illustrative purposes only and form no part of the claimed design.
